FUEL CONTAINER

Leonard Shakesby, Wolverhampton, England, assignor to Imperial Chemical Industries Limited, a corporation of Great Britain

Application September 11, 1941, Serial No. 410,460
In Great Britain September 16, 1940

12 Claims. (Cl. 150—0.5)

This invention relates to fuel containers and in particular to fuel containers having walls of non-metallic flexible or deformable material which is impervious to petrol fuels.

In the construction of fuel containers of large capacity for aircraft or the like, it is necessary to provide means to prevent surging of the fuel within the container. In containers of the kind referred to, such means usually comprise flexible baffles. The correct location and attachment of such baffles to the flexible walls of the assembled container presents considerable difficulty. Where an internal supporting structure is employed which may prevent surging of the fuel without the necessity of employing flexible baffles, it is necessary to provide means for anchoring the walls of the container to the supporting structure.

The object of the present invention is to provide a method of manufacturing fuel containers with flexible walls together with baffles and/or an internal supporting structure whereby the walls of the container may be simply and securely attached to the baffles and/or supporting structure.

According to the present invention in the manufacture of liquid fuel containers pieces of flexible non-metallic material impervious to petrol fuels are tailored and assembled to form a container having flexible fuel retaining walls with flange-like portions formed integrally thereon or firmly secured thereto and projecting into the interior of the assembled container, said flange-like portions providing for subsequent attachment of a baffle and/or internal supporting structure.

In one method of manufacturing fuel containers in accordance with the present invention, I attach securely to a sheet of flexible material one or more elongated strips of similar material in such a manner that when the said sheet of material is subsequently tailored and assembled with other suitably shaped pieces of material to form the flexible walls of the container, a portion or portions of the said strip or strips projects or project into the interior of the said container, to provide flange-like means for subsequent attachment to a baffle or supporting framework within the container.

In another method of manufacture in accordance with the present invention, pieces of flexible material are tailored and assembled to form separate sections of a fuel container, which sections are subsequently joined together around their peripheral edges to form the complete con-

tainer, the adjoining peripheral edges of adjacent sections projecting into the interior of the container and providing means for subsequent attachment of a baffle or internal supporting framework.

In one convenient method of manufacturing flexible fuel containers, a number of suitably shaped pieces of flexible material are tailored, assembled and secured together around a collapsible former or the like, which former is subsequently collapsed and withdrawn from the interior of the container through an aperture in one of its walls. When it is desired to provide a baffle or baffles within the container, the said baffle is secured in position after the former has been removed. Where this method of manufacture of the container envelope is employed, one or more strips of flexible material are provided in accordance with the present invention, for the subsequent attachment of the baffles. The said strip may be attached along its entire length, but only a part of its width, to the sheet of material as by cementing and/or sewing. The strip lies flat on the said sheet for the purpose of assembling the container, and when the collapsible former is subsequently removed, the unattached portion of the strip is folded to project into the interior of the container in the form of a continuous flange to which the baffle may be secured in any convenient manner as, for example, by riveting, cementing or sewing thereto. Alternatively, the unattached portion of the strip may be cut to form a series of tongues, which tongues may be folded to project into the interior of the container and the baffles secured thereto, either in the aforesaid manner or by looping the said tongues through slits formed in the baffle adjacent the peripheral edges thereof and securing the tips of the tongues to their roots in any suitable way, for example by riveting. If desired, the relative positions of the tongues and slits may be reversed, that is, the slits may be formed in the strip and the tongues on the baffle.

In certain circumstances, as for example where the size or shape of the container render it necessary or advisable to construct the container in separate sections and subsequently to join the sections together, the material of the container itself may be employed to provide means for the attachment of the baffles. Preferably in such circumstances, the sections to be joined together are provided with a series of slits adjacent and parallel to their marginal edges, which edges are then flanged inwardly by tailoring and pleating the material so that the slits are then located

in the flanged portions. The adjacent sections are then firmly secured together, and an internal baffle inserted through an aperture in one of the walls of the container. The said baffle is provided with a series of tongues around its periphery which tongues are adapted to be looped through the slits in the flanged portion and to be secured by riveting or the like.

Where the container is provided with an internal supporting framework, the flanged portions of the container walls may be secured to the supporting framework as well as to the baffle, or to the framework only if no baffle is provided or if the baffle is already secured to the framework. For example, the container may be provided with a skeleton framework comprising pairs of hoop-like members of angle-section placed back-to-back to form a composite T-section, and in this case, the flanged portions of the container walls may be sandwiched between and secured to the said pairs of hoop-like members. In this case, also, the flanged portion of the wall may extend beyond the hoop-members and the extended portion of the flange may be provided with tongues or slits for the attachment of a flexible baffle in the manner hereinbefore described. The said hoop-members may be spaced apart by frame-members extending longitudinally of the container, the tongues on the baffle or flanged portion being pre-arranged so that the spaces therebetween coincide with the longitudinal members and provide clearance therefor. Alternatively, the longitudinal members may comprise separate members secured to the webs of the composite T-section members.

Two methods of carrying my invention into effect are illustrated in the accompanying drawings, in which

Figure 1 is a perspective view of a flexible fuel container.

Figure 2 is a perspective view of a portion of a sheet of flexible material with a strip of similar material attached thereto.

Figure 3 is an elevation of a baffle with slits formed therein.

Figure 4 is a cross-sectional view illustrating the method of securing the baffle to the strip.

Figure 5 is an enlarged perspective view of a portion of the container of Figure 1 with a baffle secured therein.

Figure 6 is a perspective view illustrating the method of assembling separate sections of a container.

Figure 7 is an enlarged perspective view illustrating the method of securing a baffle within a container constructed in accordance with Figure 6.

Figure 8 is a cross sectional view illustrating the method of securing a baffle in accordance with Figures 6 and 7.

Figures 9 and 10 are views similar to Figures 5 and 7, illustrating other typical specific constructions within the scope of the invention.

Referring to Figures 1-5 of the drawings, a sheet of flexible material 1 has attached to it a strip 2 of similar flexible material, said strip having formed along one edge thereof a series of tongues 3. The sheet and strip material are impervious to petrol and may consist of strong fabric material treated or impregnated with a synthetic rubber-like material known as neoprene. The attachment of the strip to the sheet is effected by cementing, for example, by a solution of neoprene, and by rows of stitching 4. The said sheet of material is then assembled with

other suitably shaped pieces of material (not shown in the drawings) in known manner to form a flexible container 5 in which the sheet 1 constitutes the wall 6. The positioning of the strip 2 on the sheet 1 is predetermined in such a manner that, in the assembled container, the tongues 3 extend around the wall 6 of the container and are adapted to be folded inwardly therefrom at the position at which it is desired to attach a baffle 7. The shape of the said baffle is similar to the cross-sectional form of the container, but the dimensions are somewhat smaller. A series of holes 8 are formed adjacent the peripheral edge of the baffle, and the material between alternate pairs of holes is slit as shown at 9. The purpose of the holes 8 is to obviate elongation of the slits by tearing stresses. The baffle is also provided with conventional apertures 10, and is inserted into the container 5 through an aperture 11 in one end wall 12 of the said container. The tongues 3 are then threaded through the slits 9, folded back, and the tips of the tongues secured to their roots by eyelets 13. In carrying out this operation, it is convenient to attach first of all several tongues at suitable intervals to locate the baffle correctly, and subsequently to complete the attachment of the remaining tongues. Finally, a covering and reinforcing strip 14 is applied around the exterior of the wall 6 of the container, to obviate any leakage of fuel at the rows of stitches 4.

Referring now to Figures 6-8 of the drawings, a container similar to that illustrated in Figure 1 of the drawings is constructed by assembling several sections together. The several sections are constructed separately in any convenient manner, and two such sections are indicated by the reference numerals 15 and 16. The said sections are provided with apertures 17 and slits 18 as described hereinbefore adjacent their marginal edges and as shown in section 15 in Figure 6. The material is then pleated and tailored so that the edges are flanged inwardly as shown at 19 in section 16 in Figure 6. The apertures 17 and slits 18 are located in the flanged portion so formed. The external surfaces of the flanged portions are then coated with neoprene solution, and are brought into pressure contact, care being taken that the corresponding apertures and slits in the respective flanged portions register correctly. The fluid tight joint thus formed is reinforced by rows of stitching 20, and by the application of a covering strip 21 cemented around the exterior of the container. A flexible baffle 22 is provided with a series of radial tongues 23 around its periphery, and with conventional apertures 24. The baffle is inserted into the interior of the container through an aperture 25 in the end wall thereof, the said tongues being so arranged that when the baffle is correctly located the tongues register with the slits in the composite flanged portion in the interior of the container. The said tongues are then threaded through the corresponding slits, folded back upon themselves, and secured by eyelets as shown at 26. The correct attachment of the baffle is facilitated by first securing a few of the tongues at suitable intervals to hold the baffle in correct position, and subsequently securing the intermediate tongues.

In the construction illustrated in Figure 9, both the flange-like portion and the baffle are tongued, the flange-like portion being similar to that shown in Figures 2 and 5, and the baffle being like that in Figure 7. Both series of

tongues are looped prior to insertion of the baffle into the container. Then the baffle is secured in position by threading a cord 27 or the like through the loops on said flange-like portion and said baffle, respectively, in alternating sequence, so that the two series of loops are interlaced. The ends of the cord are then secured together by splicing or in any other suitable manner.

As shown in Figure 10, the elongated strip 28 of material which extends continuously and peripherally about the inner wall of the container may sometimes, with advantage, be folded to form a T-section and secured to the sheet of material 1 in such manner that the web 29 of the T constitutes an internal flange within the assembled container. The baffle may then be secured to said flange by any of the herein described means. For example, the double walled web of the T-section may be formed with marginal looped tongues 30 to receive beading or cord 31 passing alternately through them and through cooperating looped tongues on the baffle, in a manner like that illustrated also in Figure 9.

Whilst I have by way of example illustrated and described in detail several methods of carrying my invention into effect, it will be understood that the said methods may be modified to a considerable extent without exceeding the scope of the invention. For example, in an alternative construction (not shown) the slits may be formed in the baffle, and the member in which the slits are formed is reinforced at its edge by a beading, for example a cord or the like secured thereto in any convenient manner.

In a further modification (not shown) the strip is provided along its more central area with a series of slot-like apertures, and is secured to the sheet of material substantially by its longitudinal edges, so that those portions of the strip between the slots comprise passages through which a cord or the like may be threaded. In this case the baffle is tongued and looped, and is secured in position by a cord threaded through the loops and passages alternately in the manner hereinbefore described. Where a supporting framework is provided of which the frame-members themselves constitute means sufficient to prevent surging of the fuel or are adapted to provide such means, as for example by the prior attachment of flexible or inflexible baffles thereto, the internal flange-like means serves to anchor the walls of the container to the framework.

I claim:

1. A flexible fuel container having a plurality of longitudinally disposed sections having walls formed of flexible non-metallic sheet material impervious to liquid fuel, each of said sections being provided adjacent its longitudinal extremities with inwardly projecting flexible flanges extending continuously about the margin of said section, adjacent sections being disposed in abutting relationship and having adjacent flanges joined permanently in flatwise relationship, each flange being provided at each of a plurality of spaced localities along its margin with one element of a flexible tongue-and-slit connection adapted and arranged for interengagement with the other element of such connection provided on an internally disposed flexible baffle.

2. A flexible fuel container as defined in claim 1, provided with a sealing strip about its periphery enveloping the line of juncture between each

pair of adjacent sections and joined to said adjacent sections to prevent leakage.

3. A flexible fuel container as defined in claim 1, comprising a separate sheet of flexible material forming a flexible internal baffle member disposed within the container and having its peripheral portions secured to the said internally projecting flange-portion by such tongue-and-slit connections.

10 4. A flexible fuel container having walls formed of flexible non-metallic sheet material impervious to liquid fuel and provided with at least one continuous flange-like portion of flexible material extending continuously and peripherally around the inner wall of said container and projecting inwardly into the interior thereof, such inwardly projecting flexible flange-like portion being provided at each of a plurality of spaced localities along its margin with one element of a flexible tongue-and-slit connection adapted and arranged for interengagement with the other element of such connection provided on an internally disposed flexible baffle.

25 5. A flexible fuel container having walls formed of flexible non-metallic sheet material impervious to liquid fuel and provided with at least one continuous flange-like portion of flexible material extending continuously and peripherally around the inner wall of said container and projecting inwardly into the interior of said container, said flexible flange-like portion being provided on its interior margin with a plurality of longitudinally spaced projecting flexible tongues for spaced interengagement with an internally disposed flexible baffle.

30 6. A flexible fuel container having walls formed of flexible non-metallic sheet material impervious to liquid fuel and provided with at least one continuous flange-like portion of flexible material extending continuously and peripherally around the inner wall of said container and projecting inwardly into the interior of said container, said flexible flange-like portion being provided on its interior margin with a plurality of longitudinally spaced apertures adapted and arranged for spaced interengagement with projecting flexible marginal tongues provided on an internally disposed flexible baffle.

35 7. A flexible fuel container having walls formed of flexible non-metallic sheet material impervious to liquid fuel and provided with at least one continuous flange-like portion of flexible material extending continuously and peripherally around the inner wall of said container and projecting inwardly into the interior thereof, a flexible baffle wall disposed within the container, and means interconnecting said baffle wall and said flange-like portion, said means comprising a plurality of peripherally spaced flexible tongues projecting from at least one of the interconnected members.

40 8. A flexible fuel container having walls formed of flexible non-metallic sheet material impervious to liquid fuel and provided with at least one continuous flange-like portion of flexible material extending continuously and peripherally around the inner wall of said container and projecting inwardly into the interior thereof, a flexible baffle wall disposed within the container 45 with its outer peripheral margin operatively adjacent the inner margin of such flexible flange-like portion, and means connecting said margins and comprising tongues provided on one of said margins and looped through respectively cooperating apertures in the other, each tongue hav-

ing its extremities fastened together, for permanently holding the baffle in operative position within the container.

9. A flexible fuel container having walls formed of flexible non-metallic sheet material impervious to liquid fuel and provided with at least one continuous flange-like portion of flexible material extending continuously and peripherally around said container and projecting inwardly into the interior of said container, said flexible flange-like portion being provided on its interior margin with a plurality of longitudinally spaced projecting flexible tongues, a flexible baffle wall disposed within the container provided with spaced apertures disposed adjacent its outer peripheral margin, said tongues extending through said apertures and being looped about adjacent marginal portions of the baffle, and means fastening the extremities of the loop portions together for permanently holding the baffle in operative position within the container.

10. A flexible fuel container having walls formed of flexible non-metallic sheet material impervious to liquid fuel and provided with at least one continuous flange-like portion of flexible material extending continuously and peripherally around the inner wall of said container and projecting inwardly into the interior of said container, said flexible flange-like portion being provided with a plurality of peripherally spaced apertures, said fuel container having an internal flexible baffle wall disposed therein, said baffle wall being provided with tongue-like flexible projections disposed in spaced relationship adjacent its outer marginal periphery, said tongue-like projections passing through said apertures and being looped about adjacent sections of the said flange-like portions and fastening means securing the extremities of said loops together for

positively engaging the flange-like portions in fixed relationship.

11. A flexible fuel container having walls formed of flexible non-metallic sheet material impervious to liquid fuel, an elongated strip of material formed into a sectional T-shape and disposed peripherally about the container with the transverse portion of the T-section in flatwise relation to the wall of the container and with the web of the T-section projecting inwardly into the container to provide a continuous peripherally extending flange section, said flange section being provided on its interior margin with a plurality of longitudinally spaced projecting flexible tongues for spaced interengagement with an internally disposed flexible baffle.

12. A flexible fuel container having walls formed of flexible non-metallic sheet material impervious to liquid fuel and provided with at least one continuous flange-like portion of flexible material extending continuously and peripherally around the inner surface of said container and projecting inwardly into the interior of said container, the inner margin of said flange-like portion being provided with a plurality of peripherally spaced flexible tongues each of said tongues being looped upon itself and having the extremities of the loops secured together, a flexible internal baffle wall within said container, said wall being formed with outer peripheral marginal spaced tongues, said last-named tongues being looped and having their extremities joined, the loops of said flange-like portion and said flexible baffle wall being disposed in alternating sequence, and means passing alternately through said loops for holding the baffle wall in predetermined relation within said container.

LEONARD SHAKESBY.
